(57) CLAIM

The ornamental design for a crystal yoga mat, as shown and described herein.

DESCRIPTION

FIG. 1 is a top, front, right-side perspective view of a crystal yoga mat showing our design;

FIG. 2 is a right-side elevation view;

FIG. 3 is a left-side elevation view;

FIG. 4 is a front elevation view;

FIG. 5 is a rear elevation view;

FIG. 6 is a top plan view;

FIG. 7 is a bottom plan view; and,

FIG. 8 is a bottom, rear, left-side perspective view.

FIGS. 1-8 show a crystal yoga mat with a dotted pattern in the top section that does form a part of the claimed design.

1 Claim, 6 Drawing Sheets

US D1,071,610 S
